EDWARD R. HEWITT, OF MIDVALE, NEW JERSEY, AND ALFRED F. MASURY, OF NEW YORK, N. Y., ASSIGNEES TO INTERNATIONAL MOTOR COMPANY, OF NEW YORK, N. Y., A CORPORATION OF DELAWARE.

INTERNAL-COMBUSTION ENGINE.

1,148,774.

Specification of Letters Patent. Patented Aug. 3, 1915.

Application filed October 16, 1914. Serial No. 866,897.

To all whom it may concern:

Be it known that we, EDWARD R. HEWITT and ALFRED F. MASURY, citizens of the United States and residents of Midvale, in the State of New Jersey, and of the city of New York, in the State of New York, respectively, have invented certain new and useful Improvements in Internal-Combustion Engines, of which the following is a specification, reference being had to the accompanying drawings, forming a part hereof.

This invention relates to internal combustion engines and has for its general object the improvement of the crank casing of such engines and the simplification of the gearing for the auxiliary elements of such engines, such as the water pump, the magneto, etc., so that the gearing is made more accessible than heretofore, is less liable to injury or derangement and is susceptible of ready adjustment to change the relative phases of operation of the various parts with respect to each other.

A further object is to reduce the initial cost of manufacture of the engine crank casing by eliminating much of the machine work which is necessary in casings now known and by forming the bearings for the crank shaft, the cam shaft, and the like, in a single cap which is fastened detachably to the crank casing and constitutes part of the front wall therefor.

In a similar manner, the present invention proposes to form the driven auxiliary elements, such as the water pump, the magneto, and the like, as a single unit, and so related each to each as to permit their actuation from a common shaft.

These and other objects will appear hereinafter as this description proceeds, the invention being concerned broadly with many other features of engine construction tending to effect the general objects referred to above.

Reference is now to be had to the accompanying drawings for a detailed description of the illustrated embodiment of the invention.

In the drawings—Figure 1 is a fragmentary view in front elevation of an internal combustion engine embodying the invention and showing particularly the relationship of the crank shaft, the cam shaft and the

driving shaft for the water pump and magneto. Fig. 2 is a fragmentary view, partly in vertical section and partly in side elevation, of the engine illustrated in Fig. 1 and showing particularly the simple and compact relationship between the parts thereof.

The body portion of the crank casing *a* may be of the usual form and for this reason it has been deemed unnecessary to show all of it, the present improvements being found in the construction of one end only of the crank casing, as, for instance, the front end thereof.

Furthermore, the present improvements are not concerned with the construction of the usual engine cylinders, one of which is indicated at *b*, or the mode of mounting such cylinders on the crank casing. For the purpose of this description, however, it has been deemed desirable to indicate that the usual crank shaft *c* is driven through one or more pitmans *c'* extending from the usual pistons (not illustrated) arranged within the respective cylinders. The crank shaft *c* may find its principal bearings *a'* carried by the crank casing *a* toward the front end of the latter. On the extreme forward end of the crank shaft *c* there is secured, in the present invention, a gear *c*², which has its teeth cut along an angle of substantially 45°.

With gear *c*² meshes a similar gear *d* which is keyed on the cam shaft *d'*, one of the bearings *a'* of which is formed in the crank case *a*. It is through the engagement of the gears *c*² and *d* that the cam shaft *d'* receives its rotative movement from the crank shaft *c*. This rotative movement, in the improved engine, is further transmitted from the gear *d* to a shaft *e*, as through another spiral gear *e'*, affixed to said shaft.

From Fig. 1 it appears that the shaft *e* extends transversely across the forward end of the crank casing *a* and is connected operatively to two of the usual auxiliary elements of an internal combustion engine, namely, a water pump *f* and a magneto *g*. The construction described constitutes, in effect, a unit construction, as regards the water pump *f* and magneto *g*, although it is to be noted that the shaft *e* is detachably coupled, as at 105 *h*, to the shafts *f'* and *g'* of the water pump *f* and the magneto *g* respectively. The upper wall of the crank casing *a* is cast with an

opening through which the gear d extends to mesh with the gear e' , and this opening and the gear e' are protected by means of a suitable gear housing e^2 arranged to completely 5 inclose the gear e' and to be fastened over the gear opening to the upper wall of the crank casing a , as through bolts e^3 .

It will now appear that one of the general objects of the invention has been realized 10 by simplifying the construction and relationship of the gearing and the auxiliary elements, such as the magneto and the water pump, driven thereby, by mounting the gearing adjacent the front end of the crank 15 casing and by having a gear on the cam shaft enmeshed directly with a gear on the crank shaft, and by providing a single drive shaft for the water pump and the magneto on which is affixed a gear also directly enmeshed 20 with the said gear on the cam shaft. Not only does this construction cheapen the cost of manufacture and minimize the liability of the mentioned parts to injury and derangement, but it also facilitates the assembling 25 of all of these parts and the ready repair or replacement of any one of them.

Another feature of the invention resides particularly in the construction of that portion of the crank casing on which are 30 mounted the improved elements hereinbefore described. In carrying out such improvements to the crank casing, it has been sought to reduce as far as possible the amount of machine work required and to 35 insure ready access to the interior of the crank casing for inspection or repair, without necessitating a derangement of all of the parts connected directly or indirectly with the crank shaft. It will appear that 40 the crank casing a has an opening formed in its front wall to permit access to the interior of the casing and the edge of this opening is machined, as at a^3 , to insure the usual oil-tight union with a cap i detachably secured to the front wall of the casing 45 by means of bolts i' . The crank casing a also has its upper face machined, as at a^4 , along a single horizontal plane to afford the usual support for the cylinders b and 50 permit the attachment of the gear housing e^2 thereto, as through bolts e^3 , and also to facilitate the mounting of the pump f and the magneto g , these last named elements being formed, of course, with suitable bases, 55 indicated respectively at f^2 and g^2 , through which bases pass suitable securing bolts f^3 and g^3 respectively, into the upper face of the crank casing a . It appears from Fig. 1 that the cap i may extend slightly above 60 the upper machined edge of the casing a and be united with the base e^4 of the gear housing e^2 . In all, then, the crank casing a , in so far as concerns the mounting of the cylinders, the cam shaft, the water pump, 65 and the magneto, or like parts, need only

be machined along its front face to receive the cap i and along its upper face to receive the cylinders b and the bases f^2 , g^2 and e^4 of the water pump, the magneto, and the gear housing respectively. By disposing 70 the magneto and the water pump alongside the cylinders space is economized as the height of the cylinders determines the height of the entire motor.

The improved engine provided by the present invention also lends itself to the introduction of a further advantageous feature, namely, the formation of the bearings for the starting crank shaft and the cam shaft in the cap i , thereby greatly facilitating the assembling of the parts and the inspection of the interior of the casing. It will be seen from Fig. 2 that the cam shaft d' , or the extension thereof, on which may be fixed a governor or other needful element, is journaled in the cap i , as at i^2 , and the short cranking shaft c^3 by which initial rotation is imparted manually to the crank shaft c , in a well known manner, is also supported in the said cap. Upon the removal 85 of the cap i , the gear and other bearings for the crank shaft c and the cam shaft d' may be readily inspected, but it is to be noted particularly that the removal of the cap i and such subsequent inspection or replacement of any of the parts in the crank casing, in nowise disturbs any of the auxiliary elements, such as the water pump f , and the magneto g or the driving mechanism therefor. Conversely, it might be pointed out 90 here, that the pump f , gear housing e^2 and the magneto g , or any one of them, with their respective driving shafts and their common actuating gear e' , may be removed readily from their usual positions by removal of their securing bolts without disturbing the cap i or any of the bearings formed therein. The simplicity of this construction and the ease with which it permits the average mechanic to inspect, repair, or 100 replace, any bearing, shaft, gear, or other element needful to the efficient operation of any of the mechanism described, will commend itself to those skilled in the art.

The gears c^2 and d , by reason of the angular teeth thereon, it is evident, may be moved axially along their respective supporting shafts c , d' , so as to permit their removal from said shafts, or they may be moved axially a slight distance so as to change their angular relation to each other and thereby change to a greater or less extent the relationship between the respective phases of operation of the mechanism operatively connected thereto, such as, for instance, the timing of the valves. Such a change in the angular relation of the gears c^2 and d may be effected conveniently by removing one or the other of the said gears from their respective shafts and placing behind such removed 110

gear a shim or washer and then resecuring such gear in position on its shaft. No such shim or washer is illustrated in the accompanying drawings inasmuch as the parts are shown in their normal and proper operating relation, but the effect of such a shim, in the position indicated will be obvious.

The compactness of the improved engine and the great economy of space effected by 10 the mounting of the magneto and water pump on the crank casing in front of the cylinders, need not be elaborated on, since a comparison of this construction with those now known will make these advantages manifest.

15 Changes in the details of construction, rearrangement of the illustrated parts and substitution of other parts for those illustrated, may be made without departing from the spirit of the invention, provided all such

20 changes, rearrangements and substitutions fall within the scope of the appended claim.

We claim as our invention:

In combination, a crank casing provided with an extension at one end and having a 25 slot in the upper wall of the extension formed in the front edge thereof, a crank

shaft, a cam shaft, a gear on the cam shaft engaged operatively by the crank shaft, the gear on the cam shaft being disposed opposite said slot but having its teeth below the surface of the said extension, a magneto and a water pump both mounted on the upper face of the extension and provided with a common shaft, a gear on the common shaft extending through the said slot to mesh with 30 the gear on the cam shaft, a gear housing secured on the upper face of the extension over the slot and the last named gear, a detachable cap mounted on the end wall on said extension to afford access to the interior 35 of the casing and permit the gear on the cam shaft to be removed from the casing without disturbing the magneto, the water pump, the driving mechanism, and the housing therefor.

This specification signed and witnessed this 14th day of October A. D. 1914.
